2,244,918

DESK TELEPHONE SET

Herbert F. Obergfell, River Forest, Ill., assignor
to Associated Electric Laboratories, Inc., Chi-
cago, Ill., a corporation of Delaware

Application July 9, 1938, Serial No. 218,356

1 Claim. (Cl. 179—146)

The invention relates in general to telephone sets but more particularly to an improved desk telephone of the cradle type.

An object of the invention is to improve the construction and shape of the cover of the desk telephone.

Another object of the invention is the provision of a channel in the cover to allow a proper finger grip of the handset before removing it from the cradle, thus minimizing breakage of the handset.

A further object of the invention is the provision of means for enabling the desk telephone to be easily moved from one place to another.

A feature of the invention relates to the combination of the channel in the cover formed by the side walls and the curved rear surface and the fingers lifting plate mounted between the side walls over the channel.

Another feature of the invention relates to a pivoted fingers lifting plate for use in moving the desk telephone from place to place.

A further feature relates to the construction of the cover which is moulded in one piece and may be provided with different types of fingers lifting plates or no lifting plates, as desired, by providing different lifting plates and mounting blocks.

Other features will be apparent from the detail description of the drawings comprising Figs. 1 to 27, inclusive.

Fig. 1 shows a front view of the desk set with the calling device or dial removed.

Fig. 2 shows a rear view of the preferred embodiment of the invention with the pivoted fingers lifting plate.

Fig. 3 shows a top view.

Fig. 4 shows a perspective view.

Fig. 5 shows a cross section taken on a line approximately through the center of the desk set.

Fig. 6 shows a partial cross section through one of the side walls.

Figs. 7 and 8 show a top and side view, respectively, of the pivoted fingers lifting plate.

Figs. 9 to 12, inclusive, show various views of the mounting block for attaching the pivotal fingers lifting plate to the cover.

Fig. 13 shows a modification of Fig. 4 in perspective.

Fig. 14 shows a perspective of a modification having a combined stationary fingers lifting plate and mounting block.

Fig. 15 shows a cross-section taken approximately through the center of Fig. 14.

Figs. 16, 17, 18, 19, and 20 show various views

of the combined fingers lifting plate and mounting block.

Fig. 21 shows a perspective of another modification.

Fig. 22 shows a cross-section taken approximately through the center of Fig. 21.

Fig. 23 shows the combined fingers lifting plate and mounting block of Figs. 21 and 22.

Fig. 24 shows a perspective of a further modification.

Fig. 25 shows a cross-section taken approximately through the center of Fig. 24.

Figs. 26 and 27 show respectively top and side views of the calling device or dial mounting bracket.

Referring now in general to the drawings the cover 10 of the desk telephone is formed in one piece of some suitable plastic insulating compound and has a general shape roughly corresponding to a truncated pyramid thereby enabling ease in moulding. The base portion of the cover comprises ten sides or skirts 11 which extend substantially vertical for a short distance at which point the front, rear, and side surfaces slope inwardly. The two side surfaces 12 and 13 slope upwardly and inwardly from the skirt side portion only a short distance at which point both the side surfaces extend substantially vertical. The front surface 14 slopes upwardly and inwardly at an angle of substantially 40 degrees until it is rounded in a substantially horizontal top portion 15 which extends a short distance to the rear where it merges into the rear surface 16. The rear surface 16 extending from the rear skirts 11 to where it merges with the top portion 15 slopes upwardly and inwardly. The slope of the rear surface 16 is a perfect arc of a circle having substantially a nine inch radius. The two side surfaces form side walls 17 and 18 which extend from the top portion 15 near the front to the rear skirts 11, thereby forming a channel comprising the two inside surfaces 19 and 20 of the side walls and the curved rear surface 16. Each side wall at its highest points terminates in a pair of spaced pillars 21. The space between these pillars forming a cradle for the well-known combination transmitter and receiver handset.

A plunger 22 is movably mounted in the space between the two pillars in each side wall. These plungers are provided for operating the switch-hook springs (not shown) whenever the handset is removed or replaced on the cradle.

A base plate 23 having a rubber ring 24 is secured to the bottom of the cover by means of

screws which screw into threaded inserts in the cover.

A hole 31 is provided in the front surface through which a calling device extends, such calling device being mounted on a bracket 26 which in turn is fastened to the top horizontal portion 15 of the cover by means of screws and metal inserts in projections 30. The bracket 26 is secured to the base portion 27 by means of a shouldered female-male screw insert 28. The calling device 29 is fastened to the bracket 26 by means of machine screws and does not touch the circumference of the hole 31 in the front surface 14 at any point.

The channel formed by the curved rear surface 16 and the inside surfaces 19 and 20 of the two side walls 17 and 18 starts at the rear and gradually deepens. Its greatest depth being at a vertical point from the two rear pillars 21 in the side walls. Due to this depth of the channel the fingers can firmly grasp the underside of a handset (not shown) resting on the plungers 22 in the cradle between the pillars 21 and side walls 17 and 18. In known desk sets only the tip ends of the fingers can grasp the sides of the handset resulting in an insecure finger grip on the handset. This insecure finger grip often permits the handset to fall after it has been removed from the cradle. In case the handset slips and falls from the insecure finger tip grip considerable damage or breakage may occur.

Another advantage provided by this channel is to minimize cord interference. For example, a subscriber, in hurriedly replacing the handset on the cradle, may allow the cord extending from the desk stand to the handset, to loop between the plungers of the cradle. In many instances these loops prevent the proper depression of the plungers since the handset rests on the cord and does not depress the plungers sufficient to properly control the substation circuit. Under these conditions the telephone is temporarily out of service in regard to incoming calls. In the present invention this defect has been overcome by providing a channel which starts near the front pillars and which has sufficient depth so that the cord will not interfere with the proper operation of the plungers in case the cord is accidentally looped in between the pillars.

Mounting blocks 32 are provided between each pair of pillars 21 in the side walls. These mounting blocks 32 form the top surface of the cradle which supports the handset and are provided with threaded screw holes 36 into which the screws 42 are screwed. The screws 42 extend through holes in the switchhook spring mounting plate 43-44 and through holes in a portion of the side walls as shown in Fig. 6 and are then screwed into the mounting blocks 32 to hold the same and the switchhook spring mounting plate 43-44 firmly secured to the cover 10. A hole 37 is provided in each mounting block 32 for the plungers 22.

Due to the general shape of the cover 10 which is provided with smooth sloping sides the desk telephone is not easily moved by hand from place to place because no suitable finger grip is available for lifting the cover. In order to provide means for easily lifting and moving the desk telephone from place to place a fingers lifting plate has been provided which enables the fingers to be inserted below this fingers lifting plate in the channel formed by the rear surface 16 and the side walls 17 and 18. Several modifications of fingers lifting plates are shown in the different

figures of the drawings. The preferred fingers lifting plate 33 is shown in Figs. 2, 3, 4, 7, and 8. The lifting plate 33 has the general shape shown in Figs. 7 and 8 and has two rounded lugs 39 by means of which the plate 33 is pivoted in the cut-out rounded openings 35 in the mounting blocks 32. The lower end of plate 33 is curved as shown at 41 which allows the fingers to raise and rotate the plate 33 from the full-line position to the dotted-line position shown in Fig. 5. In the dotted-line position of Fig. 5 the plate 33 strikes against the overhanging flanges or edges 34 of mounting blocks 32, thereby preventing further rotation of the plate 33. In this raised position the fingers extend in the channel under the plate 33 and the tips of the fingers engage the cut-out portion 40, thereby giving a firm finger grip for moving the desk stand with the hand set on the cradle. The cut-out portion 40 has been carefully chosen so that the tip of the fingers will not push the handset off of the plungers when moving the telephone.

This pivoted fingers lifting plate 33 normally rests on the rear surface 16 or on the bottom of the channel as shown in full-line in Fig. 5 so as not to interfere with the fingers when removing the handset from the cradle. The combination of the pivoted fingers lifting plate 33 and the channel has a decided advantage over known desk sets in that it allows the fingers of the hand to grasp the underside of the handset, thereby providing a firm grip on the handset. This is especially true when a lifting means is provided for moving the entire telephone set, since the lifting means as a rule allows only the finger tips to grasp the sides of the handset resulting in an insecure grip of the handset. Various reports from the telephone companies show that breakage on the handsets greatly exceeds any other breakage of the desk telephones and it is thought that this new combination of the channel and pivoted finger plate will greatly reduce the breakage of handsets because of the improved finger grasping arrangement.

Figs. 14 to 20, inclusive, show a combined stationary fingers lifting plate and mounting block 50 attached to the cover 10 in the same manner as shown in Fig. 6. In this modification the combined lifting plate 50 has a flange 51 which fits in a cut-out portion of the cover 10 as shown in Fig. 15 in such a manner that the top portion of the lifting plate 50 between the two side walls 17 and 18 is substantially horizontal with the top portion 15 of cover 10. The plate 50 at its rear has an enlarged curved portion 52 provided to improve the finger grip when moving the desk telephone. It will be noted that the depth of the channel formed by the side walls and rear surface 16 is at its greatest depth directly below the rounded portion 52 of the plate 50, thereby giving sufficient room for insertion of the fingers.

An improved stationary fingers lifting plate and mounting block 60 is shown in Figs. 21, 22 and 23. This lifting plate and block 60 is secured to the cover 10 in the same manner as shown in Fig. 6. At the rear end of plate 60 an enlarged portion 61 is provided to improve the finger grip when the desk telephone is moved. The center portion of the plate 60 is cut away as shown at 62 for two purposes: one is to improve the finger grip and the other is to allow an opening for easily cleaning the channel beneath the plate. The cut-away portion 62 has been carefully chosen so as to allow the finger tips to engage the edge 62 without raising the handset away from

the plungers 22 when moving the desk telephone. Figs. 24 and 25 show a modification comprising a movable fingers lifting rod 70. The rod 70 is U-shaped and extends through holes in the rear surface and through a portion 11 of the moulded cover 10. The portion 11 being provided for guiding the movement of the rod 70. Screws 12, as shown in Fig. 25, are screwed into the lower ends of the rod 70 to limit the vertical movement of the rod when the same is raised for the purpose of moving the desk telephone. It should be noted that the horizontal portion of rod 70 does not rest on the rear surface 16. The curvature of the rod 70 from its horizontal to its vertical shape prevents the horizontal portion of rod 70 from engaging the rear surface 16 thereby leaving sufficient space between the rear surface 16 and the rod 70 to force the rod 70 vertically when the fingers are inserted beneath rod 70. The dotted-line in Fig. 25 shows the position the rod 70 attains when it is raised by the fingers for moving the desk telephone while the full-line shows the normal position of rod 70. This type of finger lifting rod, like the preferred embodiment shown in Fig. 4, permits a secure finger grip of the handset when the same is removed from the cradle because the rod 70 in normal position does not interfere with the finger tips grasping the underside of the handset.

The calling device or dial mounting bracket 26 comprises a flat metal plate of the shape shown in Figs. 26 and 27. The center of this bracket is cut away in order to provide space for the shunt and interrupter springs of the calling de-

vice. Holes 88 are provided in bracket 26 for mounting the calling device on the bracket by means of machine screws which screw into threaded holes in the casing of the calling device. The holes 81 are provided for machine screws which fasten the bracket to metal inserts in the portions 30 below the top surface 18 of the cover. The hole 82 is threaded and is secured to the base portion 27 of the cover by means of the shouldered female-male screw insert 28. The calling device is therefore mounted on the bracket 26 which in turn is mounted to top and base portions of the cover 10.

Having described the invention, what is considered to be novel is pointed out in the appended claim.

What is claimed is:

In a desk telephone, a cover formed in one piece comprising side walls each having a pair of spaced pillars forming the hand telephone supports, a rear inwardly and upwardly sloping surface between said side walls merging into a top surface, and a channel formed by said side walls and rear surface, a switchhook spring mounting plate inside said cover, a combined fingers lifting plate and mounting block on the outside of said cover for providing a finger grip to move the desk telephone and screws each extending through a hole in the switchhook spring mounting plate and a hole in the cover into a threaded hole in said combined plate and block for securing said mounting plate and said combined plate and block to said cover.

HERBERT F. OBERGFELL.
